(57) **CLAIM**

(***) Term: **15 Years**

The ornamental design for handgun proximity sensor with global positioning system (GPS) tracking, as shown and described.

(21) Appl. No.: **29/540,549**

DESCRIPTION

(22) Filed: **Sep. 25, 2015**

FIG. 1 is a perspective view of a handgun proximity sensor with global positioning system (GPS) tracking showing my new design;

(51) **LOC (10) Cl.** **10-04**

FIG. 2 is a front elevational view thereof;

(52) **U.S. Cl.**

FIG. 3 is a rear elevational view thereof;

USPC **D10/70; D22/108**

FIG. 4 is a left side elevational view thereof;

(58) **Field of Classification Search**

FIG. 5 is a right side elevational view thereof;

USPC D10/70; D22/108

FIG. 6 is a top plan view thereof; and,

CPC F41A 17/06; F41A 17/063

FIG. 7 is a bottom plan view thereof.

See application file for complete search history.

The broken line showing a micro universal serial bus (USB) port in FIG. 4 is included for the purpose of illustrating environmental structure and forms no part of the claimed design.
